[57] **CLAIM**

The ornamental design for a compartmented travel
case, substantially as shown and described.

DESCRIPTION

FIG. 1 is a perspective view of a compartmented travel
case showing my new design in the open condition;
FIG. 2 is a perspective view thereof in the closed condition;
and

FIG. 3 is a right side elevational view of the compartmented travel case shown in FIG. 1.

The characteristic feature of the design resides in the
covering on the exterior and on portions of the interior.
The bottom surface as viewed in FIG. 1 is shown in
FIG. 2.

The rear surface as viewed from FIG. 1 is the same as
the bottom surface shown in FIG. 2.
